UNITED STATES PATENT OFFICE.

ALEXANDER HAMILTON FREEMAN, OF NEW YORK, N. Y.

ELECTRICAL MATTING.

SPECIFICATION forming part of Letters Patent No. 363,290, dated May 17, 1887.

Application filed October 8, 1886. Serial No. 215,653. (No model.)

To all whom it may concern:

Be it known that I, ALEXANDER HAMILTON FREEMAN, of the city, county, and State of New York, have invented a new and useful 5 Improvement in Electrical Matting; and I hereby declare the following to be a full and clear description of the same.

The object of this invention is to form a cheap and thoroughly reliable electrical matting for use in connection with an alarm bell or gong, so that a person treading on it will press the positive and negative systems of the matting together, so as to complete the electrical circuit to the alarm, and thus sound the 15 alarm whenever any person steps on the said electrical matting.

The nature of the invention differs from electrical mattings heretofore constructed; and it consists of two sets of metallic straps or bars 20 placed one above the other, with a strap or bar of an insulating material interposed between them, the three pieces secured together in a peculiar manner, as hereinafter described, so as to crimp or bend the said straps or bars of 25 which the matting is composed in such a manner as to separate the metallic electrical conduits except when trod upon.

The invention will be readily understood by reference to the accompanying drawings, of 30 which—

Figure 1 is a general plan of the improved matting. Fig. 2 is a sectional elevation showing the three bars of which the system is composed and the manner in which those bars 35 are secured together, with crimps or longitudinal corrugations formed between the attaching-points of said bars.

The matting is formed of two sets of metallic straps or flat bars, A and A', and an intervening strap or bar, B, formed of any suitable 40 non-conducting material. The bars A and A' are riveted to the intermediate bar or strap, B, respectively, by the rivets a and a' , and the three pieces are so placed and conformed, each 45 to the other, that each of the said pieces forms crimps or longitudinal corrugations between their respective riveting-points, so as to form interstices or open spaces a^2 and a^3 , respectively, between the straps A B and A' B. The 50 rivets a and a' are placed so that their inner ends respectively terminate in the interstices

or open spaces a^2 and a^3 when the mat is lying in its normal free condition; but when a weight—as of a person treading on it—is applied to its upper side the upper strap or bar, 55 A, is pressed down toward the lower strap or bar, A', so that the inner ends of the attaching-rivets a and a' will form an electrical contact, respectively, with the opposite metallic bar, A or A', as the case may be, and thus complete the circuit and sound the alarm. In forming these compound bars into a mat the bars or straps A project beyond their fellows at one end of the mat, and are then riveted to a connecting bar, A², to one end of which is 60 attached the positive conducting-wire P, and in like manner the opposite ends of the pieces or straps A' are attached to the negative conduit-wire N. The said wires P and N connect the mat (respectively) with the battery 65 and alarm or gong (not shown) in the usual manner.

It is evident that an equivalent effect would be produced if the pieces A B A' were fastened together so that only one of them would 75 be crimped or longitudinally corrugated, in which case the insulating-piece B would lie parallel with and in complete contact with one of the metallic strips, thus forming only one set of the apertures a^2 or a^3 , (as the case may be,) and in this case the metallic strip to which the insulating-strip was permanently secured in contact throughout its entire length would be apertured, as at the dotted lines a^4 in Fig. 1, so as to completely insulate the rivets by 80 which the crimped piece was attached to the insulator B, and allow only the other set of rivets to form the make-and-break conduit.

Having described my invention, I claim—
1. An electrical alarm-mat formed of an 90 upper and a lower set of metallic strips or bars with a non-conducting strip or bar interposed between them and attached to the upper and lower metallic strips, respectively, by metallic rivets in such a form as to present crimps or longitudinal corrugations in 95 one or more of the said strips between their said points of attachment, and thereby also form interstices or open spaces between the inner ends of said rivets and the adjacent metallic strip, so as to break the electrical conduit when the mat lies in its normal condition, 100

and close the circuit or conduit when the upper section of the mat is pressed down upon the lower section, substantially as described and set forth.

5 2. The electrical mat formed of the metallic bars A and A', the interposed non-conducting bar B, the rivets a and a', and the open

spaces or interstices between the said riveted points, combined and arranged substantially as described and set forth.

ALEXANDER HAMILTON FREEMAN,
